Des. 181,555
Patented Nov. 26, 1957

181,555

COMBINED PARKING AND OFFICE BUILDING

John J. Sullivan, Norfolk, Va.

Application October 1, 1956, Serial No. 43,166

Term of patent 14 years

(Cl. D13—1)

Fig. 1

Fig. 2

Fig. 2 is an end elevational view of the building of Fig. 1.

Fig. 3 is a top plan view of the building of Figs. 1 and 2.

Fig. 4 is an enlarged fragmentary perspective view of the ramps of the building shown in Figs. 1-3.

I claim:

The ornamental design for a combined parking and office building, as shown.
